(57) **CLAIM**

The ornamental design of a handle, as shown and described.

DESCRIPTION

FIG. 1 is an isometric view of a first embodiment of a handle incorporating our new design, wherein the portions illustrated in dotted lines form no part of the claimed design, and

wherein the dotted lines around the claimed design elements provide an alterable border for the claimed design elements, such that the design elements can have the periphery defined by the dotted line or another peripheral shape;
FIG. 2 is a top plan view thereof; the bottom plan view being a mirror image thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a section view of the handle surface design from sections identified by lines 7-7 in FIG. 2;

FIG. 8 is a cross-sectional view along line 8-8 of FIG. 7;

FIG. 9 is an isometric view of a second embodiment of a handle incorporating our new design, wherein the portions illustrated in dotted lines form no part of the claimed design;
FIG. 10 is a top plan view thereof; the bottom plan view being a mirror image thereof;

FIG. 11 is a right side elevation view thereof;

FIG. 12 is a left side elevation view thereof;

FIG. 13 is a front elevation view thereof;

FIG. 14 is a rear elevation view thereof;

FIG. 15 is a section view of the handle surface design from sections identified by lines 5-15 in FIG. 10;

FIG. 16 is a cross-sectional view along line 16-16 of FIG. 15;

FIG. 17 is an isometric view of a third embodiment of a handle incorporating our new design, wherein the portions illustrated in dotted lines form no part of the claimed design;
FIG. 18 is a top plan view thereof; the bottom plan view being a mirror image thereof;

FIG. 19 is a right side elevation view thereof;

FIG. 20 is a left side elevation view thereof;

FIG. 21 is a front elevation view thereof;

FIG. 22 is a rear elevation view thereof;

FIG. 23 is a section view of the handle surface design from sections identified by lines 23-23 in FIG. 18; and,

FIG. 24 is a cross-sectional view along line 24-24 of FIG. 23.

The portions illustrated in dotted lines form no part of the claimed design.

1 Claim, 15 Drawing Sheets
